(57) **CLAIM**

The ornamental design for a cabin window assembly for vehicle, as shown and described.

DESCRIPTION

FIG. 1 is a front perspective view of a cabin window assembly for vehicle of Applicants' design in a partial environmental view;

FIG. 2 is a front perspective view of the cabin window assembly for vehicle;

FIG. 3 is a front exploded view thereof;

FIG. 4 is a front elevational view thereof;

FIG. 5 is a rear elevational view thereof;

FIG. 6 is a side view thereof;

FIG. 7 is an opposite side view thereof;

FIG. 8 is a top view thereof; and,

FIG. 9 is a bottom view thereof.

Where included, broken lines illustrate the environment in which the design is embodied and portions of the design which form no part of the claimed design.
